(57) **CLAIM**

The ornamental design for a dual strap low profile gripping device, as shown and described.

DESCRIPTION

FIG. 1 is a perspective view of a dual strap low profile gripping device according to the present design.

FIG. 2 is a top view of the design.

FIG. 3 is a bottom view of the design.

FIG. 4 is a side view of the design.

FIG. 5 is a side view of the design.

FIG. 6 is a front view; and,

FIG. 7 is a rear view.

In the drawings, the portions of the design shown by broken lines form no part of the claimed design.
